UNITED STATES PATENT OFFICE.

RANDOLPH V. WELLER, OF ROCHESTER, NEW YORK.

IRONING MACHINE.

Application filed September 24, 1925. Serial No. 58,434.

The present invention relates to ironing machines and an object thereof is to provide an ironing machine in which an ironing bed or roller and an iron are both operated through a motor and the connection between the motor and the bed is broken when the iron is positioned out of cooperative engagement with the bed. Another object of the invention is to provide a construction in which the iron and the bed are both operated through a motor, and a shiftable gear in the driving connection between the bed and the motor is thrown through a motor driven cam out of mesh with a motor driven gear when the iron is out of cooperative engagement with the bed. Another object of the invention is to provide a bed and an iron both operated by a motor, the bed being free from the motor when the iron 20 is out of cooperative engagement therewith. Still another object of the invention is to provide a construction in which a rotary bed begins to turn after an iron has come into engagement with the goods thereon but 25 before final pressure between the iron and the bed is established so that the ironing of the goods is insured and, at the same time, the shock to the machine through the iron acting as a brake to the turning of the bed 30 is eliminated. Another and still further object of the invention is to provide an ironing machine in which the bed and the iron are both moved through a motor and provision is made for permitting the iron to 35 be operated from the motor without operating the bed, so that the machine can be used for pressing goods as distinguished from ironing them. A still further object of the invention is to provide a machine 40 which is speedier in action and simpler and less noisy in operation, and which also has a minimum number of parts. Still another and further object of the invention is to provide a machine in which the operating mechanism is readily accessible without dis- 45 mantling the machine.

To these and other ends, the invention consists of certain parts and combinations of parts, all of which will be hereinafter

described: the novel features being pointed out in the appended claims.

In the drawings:

Fig. 1 is a back perspective view of an ironing machine constructed in accordance with this invention; 55

Fig. 2 is an end perspective view of the same machine;

Fig. 3 is an enlarged view showing the motor detached but with the driving gear thereof in driving relation to the ironing 60 roll;

Fig. 4 is a view similar to Fig. 3 of a more fragmentary nature showing the ironing roll out of driving connection with the driving gear; 65

Fig. 5 is a transverse section through the upper portion of the machine showing the iron in cooperation with the ironing roll or bed;

Fig. 6 is a smaller section showing the 70 iron moved out of cooperation with the bed;

Fig. 7 is a section similar to Fig. 6, showing the iron moved away from the bed when the operating cam is in position to hold the iron toward the bed; 75

Fig. 8 is a view similar to Fig. 7 showing the position of the parts when the operating cam is in its position for permitting the iron to move away from the bed, the pivot of the operating means being shifted to permit a still further movement of the iron; 80

Fig. 9 is an enlarged section on the line 9—9, Fig. 5;

Fig. 10 is a section on the line 10—10—, 85 Fig. 3; and

Fig. 11 is a section similar to Fig. 10 of a more fragmentary nature showing the clutch in clutching position.

Referring to the illustrated embodiment of the invention, 1 indicates a table having 90 supports 2 and provided at one end with a standard 3 and at the opposite end with a goose neck standard 4. These two standards in this instance support a shaft 5 of a padded bed or roll 6, the goose neck standard 4 95 permitting the tubular goods to be passed freely over one end of the bed or roller.

For cooperation with this bed or roller,

there is provided an iron comprising, in this instance, an ironing surface 7 with a heating chamber 8 in rear thereof. This iron has arms 9 extending downwardly therefrom and pivoted at 10 substantially in a vertical line with the axis of the shaft 5 with the ironing bed. The ironing surface 7 is curved to conform to the bed and the weight of the iron as a whole is such that it tends to move 10 under gravity away from the bed.

The iron is heated, in this instance, by a pipe burner 11 which preferably is mounted to turn on the iron in rear of the heating surface 7, in order that the jet openings 12 may be thrown to play the flame on the rear surface of the iron when the latter is in co-operation with the rotary bed or away from such surface when the iron is moved away from the bed.

20 In this instance, the movement of the iron and of the burner is effected through a common means comprising two links 13 rigidly connected to the tubular burner 11 and pivoted at 14 to yokes 16 which are yielding-

25 ly and adjustably mounted on the frame of the machine. In this instance, each of these yokes has a bolt 17 adjustable therein at 18 and guided longitudinally in the frame, the heads of the bolts 19 lying exposed for ad-

30 justment at the front of the machine. These bolts are surrounded by helical springs 20 each seated at one end against the frame and at the other end against a nut 21 adjustable on the bolt, for the purpose of increasing or decreasing the tension on the spring. The heads of the bolts act to limit the action of these springs, while the adjustment of the bolts in the yokes 16 align the iron with the roll.

35 One of the arms 13 on the burner is extended at 22 beyond the pivot 14 and to this arm, a link 23 is pivoted at 24, the other end of this link being pivoted at 25 through a double arm lever 26. This double arm lever is in turn pivoted at 27 to a bifurcated

40 swinging member 28 which is pivoted at 29 to the frame of the machine. Normally the swinging member 28 is held in the position shown in Fig. 6 by a detent 30 pivoted at 31 on the side frame 3 and adapted to enter a

45 notch or recess 32 in the side of the swinging member, one end of this detent being extended at 33 to provide a handle by which the detent may be manually moved to hold the swinging member in the position shown in Fig. 6 or to permit this swinging member to shift the pivotal axis 27 of the double arm lever 26 to the position shown in Figs. 7 and 8. This double arm lever 26 carries at

50 the end opposite the pivot 25 a roller 34 which cooperates with a cam 35 mounted on the side frame 3. This cam 35 is so formed or shaped that it gradually causes the iron to approach the bed or roller and to drop quickly away from the bed or roller. The

55 movement away from the bed or roller is

facilitated due to the fact that the cam compresses the spring 20 when moving the iron toward the bed and the expansion of this spring occurs on the movement of the iron away from the bed. At the same time the 70 spring acts to cushion the iron at the end of the downward movement of such iron. By moving the detent 30 to the position shown in Figs. 7 and 8, the iron can be moved away from the bed independently 75 of the cam 35, and when away from the bed can be given a still further movement as shown in Fig. 8 to permit the cleaning or waxing of the iron or the removal of the covering of the bed.

80 The cam 35 is secured by a tapered pin 36 to a stub shaft 37 which extends through the end frame 3, and is also journalled in a cover member 38 which is secured over the cam to the inner face of the side frame 3 85 by bolts 39. This casing 38 also has bearings 40 and 41, respectively, for the pivot 29 of the swinging member 28 and the pivot 31 of the detent 30.

85 In order to drive the ironing roll and at 90 the same time to operate the iron toward and from the bed or roller 6, a motor 42 is secured to a laterally extending bracket arm 43 on a two part housing 44, which is bolted to the side frame 3. This housing 44 has a 95 shaft 45 journalled therein, such shaft carrying a worm wheel 46 which meshes with a worm 47 on a motor shaft 48. Also mounted on the shaft 45 is a member 49 which has gear teeth 50 providing a gear for driving the roller or bed 6 as will be hereinafter described and which also has a hub 51 projecting therefrom and adapted to enter the pocket 52 formed in a casting 53 secured to the shaft 37 on the outside of the side frame 100 3. This casting 53 abuts a washer 54 about the shaft and the washer lies against a boss 55 on the frame 3 about the shaft 37. The members 53 and 49 act as clutch members for establishing driving connection between 105 the shaft 45 and the shaft 37. The member 49 to this end has an annular series of pockets or openings 56 and the member 53 carries the movable clutch part 57 in the form of a plunger guided in the part 53 and 110 adapted to enter any one of the pockets 56 in order to connect the shaft 37 with the shaft 45. Control of the clutch part 57 may be effected by a yoke 58 pivoted at 59 to the clutch part and at 60 to the hub of the casting 53. This yoke is moved in one direction by a spring 61 and in the other direction through a means which cooperates with a cam portion 62 on the yoke. This operating means, in this instance, is in the form of a 115 member 63 surrounding the boss 55 held thereto by the washer 54, and provided with two camming projections 64 and 65 at about 180 degrees apart. When one of these pro-

120 jections engages the cam 62, the driving con- 125

nection between the shaft 37 and the shaft 45 will be broken to permit the iron to lie in a position away from the bed, while, when the other projection engages the cam 62, the clutch plunger will be operated to break the connection between the shaft 37 and the shaft 45 to permit the iron to lie in cooperative engagement with the bed. The member 63 is, in this instance, pivoted at its upper end at 66 to an arm 67 so that the member is loosely suspended from the arm. This arm 67 is in turn pivoted at 68 and is connected to a finger bar 69 arranged in the recess 70 formed in the table over which the clothes are passed to the bed 6 in order to be carried in contact with the iron. Normally, the finger bar is held in a raised position through spring means 71 and holds the projections 64 and 65 in the path of the cam 62, but with the depression of said bar, the projections 64 and 65 move downwardly and the one in engagement with the cam frees the yoke lever 58 so that the plunger 57 will move into one of the pockets 56 and establish driving connection with the shaft 45. The finger bar being immediately released causes the other projection 64 or 65 to move into position to engage the cam 62 and break connection between the shaft 37 and the shaft 45 when the cam will have moved about 180°.

Secured on the shaft 5 of the roller 6 and on the outside of the frame 3 by a taper pin 72^a is a gear 72. Also mounted to turn on the shaft 5 is a bifurcated or yoke member 73 which straddles the gear 72 and has a shaft 74 journaled thereon and carrying a small pinion 75 meshing with the gear 72. These parts are held to the shaft by the taper pin 72^a which holds the gear 72. This shaft 74 also carries a gear 76 which is adapted to mesh in turn with the gear 50 on the casting 49 so that from the shaft 45 the ironing roller 6 may be turned. The teeth of the gears 50 and 76 are beveled or backed off so that they tend to mesh when thrown one in engagement with the other.

It is desirable to stop the rotation of the bed or roller when the iron is away from the bed, so that the goods will not be fed over the bed before they are ironed. This result of stopping the turning of the bed is secured in this instance by making the surface of the casting 53 in the form of a cam 55 or eccentric 77 and engaging this cam by a roller 78 journaled on the swinging yoke 73. This cam 77 is so formed and timed that the iron contacts with the bed to engage the goods to be ironed before the bed begins to move; but before the final pressure of the iron on the bed takes place, the gear 76 is in driving relation with the gear 50 and the bed begins to turn. This time of the commencement of the turning of the bed is important, as a shock on the motor does not take

place through the pressing iron acting as a brake on the ironing roll.

In some instances, it is desirable to prevent the operation of the bed or roller 6, while, at the same time, permitting the iron to cooperate with the bed, as when it is desired to press goods instead of iron them. This result, in this instance, is secured by providing a latch or detent 79 pivoted at 80 to the side frame and having a handle 81 through which the detent may be operated. Normally this detent lies in the position shown in dotted lines in Fig. 4 out of engagement with the swinging member 73, but, after the cam 79 has shifted the gear 76 out of mesh with the gear 50, this detent may be moved to the position shown in full lines in Fig. 4 against the abutment 82, so that upon the dropping of the swinging frame 73 by means of the cam 77, a shoulder or abutment 83 on the swinging member 73 will engage the detent 79, and, with the detent, hold the swinging frame in such a position that the gear 76 is not in mesh with the gear 50, and, as a consequence, the iron may be moved toward and from the bed to perform a pressing operation as distinguished from an ironing operation when the bed rotates.

The operation of the invention will be understood from the foregoing but it may be summarized as follows:

Assuming that the parts are in the positions shown in Fig. 6 and it is desired to start ironing, the motor being running, the operator depresses the finger bar 69 which throws the lug 64 out of engagement with the cam 62 permitting the clutch part 57 to move into engagement with the member 49, thus effecting driving connection between the shaft 45 and the shaft 37 turning the cam 35 to the position shown in Fig. 5. Just before the final pressure of the iron 7 on the roll 6, the cam 77 lowers the gear 76 into engagement with the gear 50, so that driving connection between the gear 50 and the gear 72 on the shaft of the roll 6 is established, causing the roll 6 to turn. This turning continues due to the fact that the cam 77 stops rotating after it is turned 180 degrees, because the cam surface 62 engages with the camming projection 65 and shifts the clutch member 57 out of connection with the member 49. This also stops the action of the operating mechanism for the shoe including the cam 35 and the parts operated thereby and the shoe maintains its position against the roll or bed. When it is again desired to separate the bed and the shoe, the finger bar 69 is again depressed, causing the projection 65 to shift out of engagement with the camming surface 62, so that the clutch member 57 will shift into engagement with the member 49, thus again turning both the cams 35 and 77, the cam 35 effecting the shifting of the iron away from the bed 6

and the cam 77 causing the gear 76 to be thrown out of mesh with the gear 50, thereby stopping the rotation of the roll, when the iron is shifted away from the bed.

5. The housing 44 with the shaft 45 and parts mounted thereon forms a separable driving unit which may be quickly removed to view or repair interior parts, and the hub 51 by entering the pocket 52 tends to align the parts quickly when the unit is fitted to the machine.
10. What I claim as my invention and desire to secure by Letters Patent is:

1. An ironing machine comprising a rotary bed, an iron, a motor, means operated by the motor for effecting relative movement between the iron and the bed, a clutch connection between said motor operated means and the motor, a driving connection 15 between the motor and the bed connected with the motor at a position in advance of the clutch between the motor and said motor operated means, a breakable connection in the driving connection between the rotary bed and the motor, and means for making and breaking such breakable connection operated by a part movable with the motor operated means which effects relative movement between the bed and the iron and connecting with said motor operated means at a point on that side of the clutch remote from the motor.
2. An ironing machine comprising a rotary bed, an iron, a motor, a connection between the motor and the bed for turning the latter, means operated by the motor for effecting relative movement between the iron and the bed to bring the two into and out of cooperative engagement, and means operated by the motor for breaking the driving connection between the motor and the bed upon the separation of the iron and the bed, said means effecting the establishment of such driving connection after the iron engages the material on the bed but before the final compression between the iron and the bed.

3. An ironing machine comprising a rotary bed, an iron movable toward and from the bed, means effecting the movement of the iron toward and from the bed, a motor driven shaft, a driving connection between the motor driven shaft and the bed embodying a shiftable gear, an operating connection between the motor driven shaft and the iron, and a cam driven in timed relation to the operating mechanism of the iron and operative on said shiftable gear to shift said gear in order to break the driving connection between the motor driven shaft and the bed when the iron is moved away from the bed.
4. An ironing machine comprising a rotary bed, an iron movable toward and from the bed, a motor driven shaft, operating mechanism for the iron, a clutch connection

between said operating mechanism and the motor driven shaft, a cam moved with said operating mechanism for the iron, a gear driven by the motor driven shaft, a gear on the shaft of the bed, a swinging frame, at least one gear on said frame establishing driving connection between the gear on the motor driven shaft and the gear on the shaft of the bed, and means on said frame for cooperating with the cam to cause said swinging frame-carried gear to be thrown into and out of driving connection between the motor driven shaft and the bed.

5. An ironing machine comprising a rotary bed, an iron movable toward and from the bed, a motor driven shaft, operating mechanism for the iron having a shaft axially aligned with the motor driven shaft, a cam on the second named shaft, a clutch connection between said second named shaft, and the motor driven shaft, a gear on the motor driven shaft, a swinging gear interposed between the last mentioned gear and the bed, and a support for said swinging gear having means for cooperating with the cam to cause the cam to make and break the driving connection between the motor driven shaft and the bed.

6. An ironing machine comprising a rotary bed, an iron movable toward and from the bed, a motor driven shaft, operating mechanism for the iron having a shaft axially aligned with the motor driven shaft, a cam on the second named shaft, a clutch connection between said second named shaft and the motor driven shaft, a gear on the motor driven shaft, a swinging gear interposed between the last mentioned gear and the bed, a support for said swinging gear having means for cooperating with the cam to cause the cam to make and break the driving connection between the motor driven shaft and the bed, and means for locking said gear out of driving connection to permit the iron to be operated from the motor driven shaft without operating the bed.

7. An ironing machine comprising a rotary bed, an iron movable toward and from the bed, a motor driven shaft, operating means for the iron moved by the motor driven shaft, a clutch interposed between the motor driven shaft and the iron operating means, a driving connection between the motor driven shaft and the bed in advance of said clutch for effecting the turning of the bed, said driving connection having breakable means for the breaking of said connection, and means operated by the motor driven shaft on the opposite side of the clutch for effecting the breaking of said connection when the iron is moved away from the bed to stop the turning of the bed.

8. An ironing machine comprising a rotary bed, an iron movable toward and from the bed, a motor driven shaft, a gear on said

- shaft provided with pockets in one face, an operating mechanism for the iron having a shaft aligned with the motor driven shaft, a cam on said shaft, a clutch member movable transversely through the cam and adapted to enter any one of the pockets of the adjacent gear, a driving connection between the gear on the motor driven shaft and the bed embodying a shiftable part, and means connected with said shiftable part and cooperating with the cam to effect the making and breaking of the connection between the motor driven shaft and the bed.
9. An ironing machine comprising a rotary bed, an iron, mechanism for effecting the relative movement between the iron and the bed, a motor driven shaft for operating said mechanism, a clutch interposed between the shaft and said mechanism and having a clutch element joining portion rotatable with said mechanism, a pivoted arm, and a clutch controlling member pivotally suspended from said arm and having two rigid cam projections lying on opposite sides of the axis of turning of the clutch to cooperate with the joining portion of said clutch in order to break connection between the motor driven shaft and said mechanism on each 180° of turning of the clutch.
10. An ironing machine comprising a rotary bed, an iron pivotally mounted to move toward and from the bed, a member supported by the iron to turn about an axis to one side of the pivotal axis of the latter, two arms extending from said member one at each end of the iron, longitudinally movable spring pressed plungers to which said arms are pivoted, said plungers being guided in fixed parts of the machine, and means having connection with said turning member to move the iron toward and from the bed and swing said arms against the action of the spring pressed plungers.
11. An ironing machine comprising a rotary bed, an iron pivotally mounted to move toward and from the bed, a member supported by the iron to turn about an axis to one side of the pivotal axis of the latter, two arms extending from said member one at each end of the iron, and longitudinally movable spring pressed plungers to which said arms are pivoted, said longitudinally movable spring pressed plungers being movably mounted in the frame of the machine and adjustable in length for the purpose of varying the pressure of the iron on the bed, and means having connection with said turning member to move the iron toward and from the bed and swing said arms against the action of the spring pressed plungers.
12. An ironing machine comprising a rotary bed, an iron pivotally mounted to move toward and from the bed, an arm mounted to turn on the iron at one side of the pivotal axis of the latter, a yoke pivotally connected to the arm, a bolt adjustably connected to said yoke and having a head exposed to permit adjustment, an abutment cooperating with the head of the bolt to limit the opening movement of the iron, a spring having an abutment against a fixed part of the machine and surrounding said bolt and connected thereto to yieldably support said bolt and means for swinging the arm against the action of the spring.
13. In an ironing machine the combination with a rotary bed, and an iron pivotally mounted to swing toward and from the bed, of operating means for the iron embodying a cam, a two armed lever, a swingable member pivotally supporting said two armed lever, one arm of the lever cooperating with the cam on one side of the axis of the latter, releasable means for holding said swingable member against movement, a link pivotally connected to the other arm of the lever, an arm pivotally mounted on the iron on an axis to one side of the axis of turning of the iron and pivotally connected with the link, a yieldably mounted member to which said arm is pivoted, and means for supporting said yieldably mounted member.
14. An ironing machine comprising a rotary bed, an iron pivotally mounted to swing toward and from the bed, an operating means for the iron embodying a cam, a two armed lever, a swingable member pivotally supporting said two armed lever and one arm of the lever cooperating with the cam, a connection between the iron and the other arm of the lever and a pivoted detent arranged to engage the swingable member to one side of its pivot to hold the two armed lever in operative relation with the cam.
15. An ironing machine comprising a frame, a rotary bed on the frame, an iron on the frame, and two shafts on the frame, one for effecting the movement of the iron toward and from the bed and the other for effecting the movement of the bed, a removable driving unit for both shafts having a single shaft, separate means for effecting driving connection with both shafts, a part of each of said means being carried by the single shaft, and means for aligning said single shaft with one of the shafts on the frame.
16. An ironing machine comprising a frame, a rotary bed on the frame, an iron on the frame, two parallel shafts on the frame, a removable driving unit having a single shaft, a clutch for connecting one of said frame shafts with the single shaft when the two shafts are aligned, a gear on the single shaft, and means providing driving connection between the gear and the other shaft on the frame.
17. An ironing machine comprising a rotary bed, an iron pivotally mounted to move

toward and from the bed, an arm mounted to turn on the iron at one side of the pivotal axis of the latter, a yoke pivotally connected to the arm, a bolt adjustably connected to said yoke and having a head exposed to permit adjustment, an abutment cooperating with the head of the bolt to limit the

opening movement of the iron, a spring having abutment against a fixed part of the machine and surrounding said bolt and connected thereto to yieldably support said bolt and means for swinging the arm against the action of the spring.

RANDOLPH V. WELLER.
